UNITED STATES PATENT OFFICE

CHARLES WEBER, OF NEWARK, NEW JERSEY, ASSIGNOR, BY MESNE ASSIGNMENTS, TO PEGGY O'NEAL CIGAR CORPORATION, OF NEW YORK, N. Y., A CORPORATION OF NEW YORK

COIN-CONTROLLED VENDING DEVICE

Application filed November 5, 1929. Serial No. 404,880.

This invention relates to vending machines and more particularly to devices for controlling such machines by means of a coin.

5 Since the primary object of a vending machine is to dispense with the services of an attendant, it is essential that such a machine be operable at all times. In one form of vending machine there is used a pair of discs having normally aligned slots into which a coin may fall to couple the two discs together, so that movement of an external crank may be transmitted to the dispensing mechanism of the machine.

10 15 However, this rather simple form of coin-controlled device has been found objectionable in that it frequently happens that the slots in the discs are not aligned, with the obvious result that the coin cannot enter the slots in the discs to couple them together, and the dispensing mechanism may not be operated.

It is an object of this invention to provide in a vending machine a coupling device comprising a pair of slotted discs provided with means for assuring the alignment of the slots in the discs.

20 25 This and other advantages, which will later appear are accomplished by the simple and practical construction and arrangement of parts hereinafter described and exhibited in the accompanying drawings, forming part hereof, and in which:

30 35 Figure 1 represents a front elevational view partly in section of my improved vending machine.

Figure 2 represents a view taken on line 2-2 of Figure 1.

40 45 Figure 3 is a cross-sectional view of a coupling device used in the machine.

Referring to the drawing, the vending machine is shown to include a substantially rectangular casing 5 having a door 6 hinged thereto, the latter being provided with a glass window 7 by means of which the contents of the casing may be inspected.

50 The casing is divided by a partition 8 into a large compartment in which the commodity being vended is carried, and a small com-

partment in which the coin-control mechanism is positioned.

In the present case, the machine is designed to vend cigars or articles of a similar shape which are capable of falling into a dispensing trough 9 in the large compartment. The trough 9 is fixed to a shaft 10 journalled in the casing wall 11 and the partition 8, the shaft 10 extending through the partition 8 into the small compartment, in which space 55 it has fixed thereto a disc 12 having a transverse slot 13.

The disc 12 has an integral projection 12' upon which is rotatably mounted a disc 14 having a transverse slot 15. The disc is provided with an integral shaft 16, which is journalled in the wall 17 of the casing 5.

55 60 Fixed to shaft 16 is a gear 18 in mesh with a larger gear 19, the latter being fixed to a shaft 20 journalled in and passing through the wall 17 to the outside of the casing where the shaft 20 has fixed thereto an operating handle 21.

65 A tension spring 22 has one end attached to a lug 23 projecting from the side of gear 19 and the other end attached to the wall 17.

70 75 Fixed to the periphery of disc 14 is a transverse arm 24 extending over disc 12 and in the path of a pin 25, projecting radially from disc 12.

80 85 A pin 26 projects axially from the side of disc 12 and is adapted to be stopped by a lug 27 projecting from the rear wall of casing 5. In the small compartment is mounted a chute 28 for guiding a coin into the slots 13 and 15. Movement of the handle 21 is limited by pins 29 and 30 projecting from the outer side or wall 17.

90 95 In operation, a coin is dropped into the chute 28 and falls into the slots 13 and 15, thus coupling discs 12 and 14 together. Rotation of handle 21, through gears 18, 19 and shaft 16 will cause disc 14 to rotate disc 12, and consequently rotate the trough 9 to dispense the cigar or other commodity through an opening in the casing 5.

100 As seen in Figure 1, the rotation of the discs 12 and 14 will be clockwise, and consequently the arm 24 moves in advance of the pin 25. As soon as pressure is removed from the han-

dle 21 the spring 22 tends to rotate the disc 14 in a counter-clockwise direction, and arm 24 engages pin 25 to rotate the disc 12 in the same direction. The counter-clockwise movement of the disc 12 is limited by the engagement of pin 26 with the lug 27.

It will be seen that normally arm 24 engages pin 25 and pin 26 engages lug 27, these parts being so arranged that normally slots 13 and 15 will be in alignment to receive a coin passing through the chute 28.

From the above description it will be seen that I have provided a simple yet positive means for assuring the alignment of the slots in the coupling discs, thereby assuring the operation of the dispensing mechanism whenever a proper coin is inserted into the machine.

It will be noted (see Fig. 3) that the slot in disc 12 is very shallow, while the slot in disc 14 is relatively deep, so that the clutch member 12 has sufficient bearing upon the coin to make the clutch operative. But in the event that a slug of very thin metal or pasteboard, such as have been heretofore surreptitiously used, is inserted, such a slug would not have sufficient strength to operate the two clutch members 12 and 14. The small recess 13 in clutch member 12, owing to the small bearing which it has on the slug, would bend the narrow portion of the slug engaged in the recess and consequently only one member of the clutch would rotate.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

- 45 1. In a vending machine, a coupling device comprising a pair of discs having transverse peripheral slots adapted to receive a coin, a shaft upon which one of the discs is fixed, the second disc being independently rotatable with respect to the first disc a pin projecting radially from the first disc, an arm mounted on the second disc and projecting over the first disc in the path of said pin so that rotation of the second disc will cause rotation of the first disc, a pin projecting axially from a side of the first disc, a stop in the path of said pin to limit the movement of the first disc in one direction and resilient means to normally urge the second disc to rotate in a direction so that said arm will engage the radial projecting pin on the first disc.
- 55 2. In a vending machine, a shaft having a disc fixed thereto, a second disc rotatably mounted adjacent said disc, slots in the discs adapted to receive a coin to couple the discs

together, means for rotating the second disc in one direction, resilient means to normally rotate the second disc in the opposite direction, a pin projecting radially from the first disc, an arm on the second disc adapted to engage the pin to cause the first disc to follow the movements of the second disc, a pin projecting from the first disc, and a stationary lug in the path of said pin to stop the rotation of the discs in a position so that the slots will be in alignment.

This specification signed this 25th day of October, 1929.

CHARLES WEBER.
